UNITED STATES PATENT OFFICE.

FRANCES NEWTON RENFROW, OF YAZOO CITY, MISSISSIPPI.

WIRE-STRETCHER AND FENCE MENDER AND TIGHTENER.

1,108,397.

Specification of Letters Patent. Patented Aug. 25, 1914.

Application filed August 18, 1913. Serial No. 785,420.

To all whom it may concern:

Be it known that I, FRANCES NEWTON RENFROW, a citizen of the United States, residing at Yazoo City, in the county of Yazoo and State of Mississippi, have invented a new and useful Wire-Stretcher and Fence Mender and Tightener, of which the following is a specification.

The device forming the subject matter of this application, is adapted to be employed for stretching the wires of a fence, for pulling staples, and for other operations met with in fence building.

The invention aims to provide a tool of the type described which may readily be manipulated with one hand to effect certain operations hereinafter referred to.

Another object of the invention is to provide a device of this type which may be employed for putting a kink in a loose wire.

The invention aims to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawing:—Figure 1 shows the invention in perspective; Fig. 2 is an end elevation.

The tool herein disclosed comprises a pair of intersecting, pivotally connected members, denoted respectively by the numerals 1 and 9. These members preferably are fashioned from iron or steel, and are circular in transverse section.

The member 1 is substantially straight from end to end and comprises a handle 2, the handle 2 being widened as indicated at 3 to form a flat head 4, the head 4 being reduced as indicated at 5 and broadened as indicated at 6. The broadened end 6 of the member 1 is bifurcated as shown at 7 to form prongs 8.

The member 9 of the device, which is disposed in intersecting relation to the member 1 is bent upon itself intermediate its ends as shown at 11 to form a handle 10 which projects toward the handle 2 of the member

1, the handle 10 being disposed substantially at right angles to the main or shank portion of the member 9. The member 9 is broadened as indicated at 12 to form a flat head 14, the extremity of the head 14 being broadened as indicated at 15, the broadened portion 15 being curved as indicated at 16, and being bifurcated as shown at 17 to form claws 18. A pivot element 19 connects the flat head portions 4 and 14 of the members 1 and 9 respectively.

The device may be operated in a variety of ways, some of which will be set forth, others of which will suggest themselves readily to the user.

If desired, the edge 20 of the member 1 may be placed against a post, the wire which is to be stretched being engaged between the claws 18. Then, if the member 1 is swung in the direction of the arrow A, it will be obvious that the wire will be tightened, whereupon the wire may be secured to the post, either by passing a wire around the post, or by stapling the stretched wire to the post, as is customary. It is possible, also, to tighten up a slack wire between a pair of posts. Under such circumstances, the prongs 8 of the member 1 are straddled on the wire and the member 1 is rotated through the medium of the member 9, the handle 10 of which will act as a crank.

The prongs 8 may be employed for pulling staples.

The device herein disclosed is preferably made in a small form, so that the hand of the operator, may, if desired, engage the handles 2 and 10. When the edge 20 is in abutment with the post, and when the member 1 is swung around in the direction of the arrow A, the wire being engaged between the claws 18, there is a tendency, obviously, for the claw carrying end 16 of the member 9 to swing away from the post, thus spacing the stretched wire apart from the post, so that the wire cannot be stapled down readily. This operation, may be obviated, if the hand of the operator is engaged simultaneously with the handles 2 and 10. By this operation, the claw carrying end of the member 9 may be held close to the post, so that the stretched wire may be stapled in place or otherwise secured.

Having thus described the invention, what is claimed is:—

A wire stretcher comprising a pair of primary and secondary members pivotally con-

ADJUSTABLE SWIVELING PAPERCLIP CLIP

ected intermediate their ends, the primary member being substantially straight, one end of the primary member constituting a post engaging fulcrum and the other end of the primary member constituting a handle; the secondary member terminating at one end in a wire grip located opposite to the fulcrum end of the primary member and the other end of the secondary member terminating in an angularly disposed handle projecting toward the handle of the pri-

mary member and adapted to be grasped simultaneously therewith to swing the grip of the secondary member toward the fulcrum end of the primary member.

15

In testimony that I claim the foregoing as my own, I have hereto affixed my signature in the presence of two witnesses.

FRANCES NEWTON RENFROW.
